UNITED STATES PATENT OFFICE.

DORA THORSTEINSON, OF POINT ROBERTS, WASHINGTON.

DESIGN FOR A STOVE.

Application filed April 30, 1929. Serial No. 31,050. Term of patent 3½ years.

To all whom it may concern:

Be it known that I, DORA THORSTEINSON, a citizen of the United States, and a resident of Point Roberts, in the county of Whatcom and the State of Washington, have invented a new, original, and ornamental Design for Stoves, of which the following is a specification, reference being had to the accompanying drawings, forming a part thereof.

In the drawings:

The figure is a perspective view of the stove showing my new design.

I claim:

The ornamental design for a stove, as shown.

DORA THORSTEINSON.
